Primary Examiner — Thomas Johannes
Assistant Examiner — Shawn T Gingrich

(57) **CLAIM**

The ornamental design for an optical connector for optical fiber, as shown and described.

DESCRIPTION

FIG. 1 is a perspective view of an optical connector for optical fiber;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view showing the design together with a screw cap and an optical cable.

The broken lines portion of the figure drawings is included to show portions of the article that forms no part of the claimed design.

1 Claim, 8 Drawing Sheets
